APPARATUS FOR HEAT TREATING STRIP METAL

William R. Webster, Bridgeport, Conn.

Application June 3, 1937, Serial No. 146,153

3 Claims. (Cl. 266—3)

This invention relates to an apparatus for heat treating metal and more particularly for heating metal in strip form for annealing and similar purposes, such as described and shown in my earlier 5 Patent No. 1,971,666, of August 28, 1934.

As stated in the said patent, in producing brass and other cold rolled metal strips, it is necessary to heat the strip at intermediate stages and also as a final operation for the purpose of annealing 10 it. To meet the requirements of the trade, it is essential that the metal be heated within very close temperature ranges in order to give it the required properties.

In my said earlier patent the method consists 15 of heating a metal strip to a uniform temperature by heating the wall of a rotary drum about the periphery of which the strip is passed, so that the strip lies in contact with the heated surface of the drum and is moved along with it as the 20 drum is revolved. The drum is heated from the inside and the heat passes from its internal surface to its exterior surface, and by controlling the temperature of the exterior surface upon which the strip bears, and the speed at which the strip 25 travels through its path or orbit, it is possible to obtain a nice control of the metal temperature, and it is also possible to heat all portions of the strip uniformly and in a manner which is convenient for the operator.

It is the main object of my present invention 30 to improve the operation, construction and efficiency of the apparatus described in my said earlier patent by the provision of means which will regulate the input of heat into the moving 35 metal body depending upon the variations in the temperature of the metal itself.

This object is accomplished as follows: By directing a heat responsive device, for example, a well known type of radiation pyrometer against 40 the metal strip as it leaves the heat imparting medium, and by using this pyrometer or other heat responsive device in conjunction with an electric control device which also may be of well known construction and in conjunction with suitable speed changing means which may be of well 45 known types, the speed of the metal strip can be controlled to regulate its temperature. In other words, by this means the speed of the metal is made responsive to any variation in the final 50 temperature of the metal.

I have found that by employing structure embodying the above named apparatus, the close regulation of the temperature of the heat imparting medium itself requisite in my said earlier 55 patent can be dispensed with.

With this and other objects in view, my invention consists in the novel construction, combination and arrangement of parts as will be herein- 60 after more fully described and defined in the appended claims.

In the accompanying drawing in which similar reference characters denote corresponding parts:

Figure 1 is a more or less diagrammatic side elevation of annealing apparatus constructed in accordance with my invention showing the application of speed changing mechanism to the heating drum; 5

Figure 2 is a similar view of a modified form of construction showing the application of speed changing mechanism to the pinch rollers used for 10 feeding the metal strip;

Figure 3 is a similar view of another modified form of construction employing a stationary heating device and speed changing means in connection with the winding drum for the metal strip. 15

Referring first to Fig. 1 of the drawing, A is a cylindrical drum of heat resisting material such as nichrome which has a flanged portion B at one side by means of which it is mounted on a suitably supported shaft (not shown), the shaft being 20 fixed to the drum and adapted to rotate on suitable bearings (not shown). A burner H is supported in the interior of the drum. This burner may be of any suitable kind, but in the present instance it is shown as a gas burner supplied with 25 gas and air through the pipes L and K respectively. Closing contiguous to the drum A are two rollers E and E' respectively which are arranged close together and whose axes are parallel to that of the drum A. The coil of metal N to be annealed is mounted on a suitable support O and the strip from the coil is passed around the roller E, thence around the drum A, and thence around the roller E', from which it passes to a winding device or blocker I which is suitably driven from 30 a motor J by a slip drive such as belting or the like. 35

The burner H in the drum A presents a plurality of nozzles directed axially of the drum and located near its circumference at a number of 40 points. Four of such nozzles are shown in the present instance. This burner structure is stationary, and the drum A having the thin cylindrical wall about which the strip is passed rotates about said burner structure. The burner structure by sending flames outward against or into close proximity to the inner circumference of the cylindrical strip-contacting wall, heats said wall to a uniform degree throughout the periphery of 45 the drum.

By controlling the speed at which the drum A is rotated (in Fig. 1) the temperature of the metal can be maintained within very close limits, and the softness of the metal as measured by the crystal size thereof controlled within exceedingly 50 close limits which is a highly desirable result in this art.

In order to maintain a uniform degree of contact between the strip and the surface of the drum, a tensioning device Q of any well known 55

50

40

50

55

60

form is employed which is capable of being adjusted by means of a screw or wedge (not shown).

Strip metal of the character in question sometimes contains a certain amount of oil, the burnt products of which are apt to build up on the surface of the drum so as to reduce the transmission of heat between the drum and the strip. To prevent this, a block of suitable abrasive material R is maintained in contact with the surface of the drum so that the burnt products are continuously scraped off and the contact heat resistance between the drum and the strip maintained at a constant point.

After having been placed in position about the drum in the manner shown in Fig. 1, and after initiating the drive of drum A and the drive of the blocker I at a suitable slow speed, the strip can be passed over a large part of the round hollow heating structure, preferably with the strip pulling along the drum so that a given point on the strip surface maintains contact with a given point on the drum surface until the strip portion in question passes to roller E.

In order to maintain the operation continuously, a duplicate of the support O (not shown) and a duplicate of the winding device I (not shown) are provided, and as the inner end of the coil is reached, the outer end of the succeeding coil is attached thereto by well known means. As the joint between the two coils reaches the winding device I, the two coils are separated by a shearing device (not shown) and the end of the second coil is wound on the duplicate winding device.

In order to vary the speed of the strip for variation of the amount of heat imparted thereto by the drum A, I control the driving speed of the drum A as follows:

A suitable heat responsive means as radiation pyrometer P of well known type and construction is directed against the strip of metal preferably as it leaves the drum A. This pyrometer P is electrically connected as by wires 1 and 2 to a suitable electric balancing device 11, such as for example, one commonly known in the industry as a "Micromax Electric Control" which is a sensitive balance for regulating input in proportion to demand, and usually comprises an electric controller unit and a relay detector unit the two being diagrammatically illustrated at 11^a and a reversible motor drive mechanism illustrated diagrammatically at 11^b. These three which are electrically and mechanically interconnected combine to form a sensitive electrical balance. Any disturbance, due to a fluctuating in the condition being controlled (temperature here) is quickly detected resulting in immediate correcting movement of the motor drive mechanism 11^b. In the embodiment of Fig. 1 the motor drive mechanism 11^b of the electric control device may be mechanically coupled through the worm 12 on its motor shaft and the worm gear 13 to the regulating mechanism 14 of a speed changing means G. The input shaft 15 of said means G is suitably driven as by a motor (not shown) and the output shaft 16 whose speed is varied in well known manner by the operation of the regulating mechanism 14, which latter changes the effective diameters of the belt connected pulleys on the two shafts by shifting opposing cone faces thereof (not shown) toward or away from each other in well known manner, serves to drive the drum A through a chain 15' and sprockets on shaft 16 and the shaft of the drum A, or in any other well known manner.

Operation is as follows:

The controller device 11^a by a suitable control setter 11^c thereon is set to the desired temperature of the metal strip. The radiation pyrometer P detects any change in temperature in the metal strip as it leaves the drum A, electrically transmits this change to the electric balance 11, which being thereby unbalanced, causes its motor drive mechanism 11^b through the worm gear coupling 12, 13 to operate the speed changing means G and thus alter the speed of drum A and the speed of the metal strip over the heating drum A and thereby corrects the temperature variation of the metal strip from the required point. Thus, should there be a tendency for the temperature of the metal strip to rise above the required point, the radiation pyrometer P, which functions without appreciable lag, will operate to increase the speed of the metal in its passage around the heated drum A. On the other hand, should the temperature of the metal tend to fall below the required point, the speed of the metal would be automatically reduced so that the metal absorbs more heat from the drum and its temperature consequently rises.

An alternative speed control for the metal strip is shown in Fig. 2. Herein a pair of driving pinch rollers F constituting strip feeding and unwinding means are applied to the strip between the roller E' and the winding device or blocker I. These rollers F between which the strip passes are driven by a motor 17 through a speed change mechanism Y. As shown in this modification this mechanism Y includes a hollow input disk 19 and a hollow output disk 20, the first coupled to the drive shaft of the motor 17 and the other to an intermediate shaft 21 which latter suitably serves to drive the pinch or feeding rollers F through suitable gearing (not shown) and the chain drive 21' or the like. Upon tilting of the intermediate rolling disks 23 and 24 which bear on the surfaces of the disks 19 and 20 in the annular hollows thereof, the speed of the output disk 20 relative to the input disk 19 may be regulated within desired limits. Tilting of said roller disks 23 and 24 is effected as follows:

The shaft of the motor drive mechanism 11^b of the electric balancing unit 11 is provided with a crank 25, which latter through the link 26 is connected to the control crank 27 which is suitably coupled to the roller disks whereby movement of the crank 25 is transformed into tilting of the disks 23, 24. Operation in this modification is very similar to that of the first. The radiation pyrometer P detects any change in temperature of the metal strip, transmits this electrically to the electric balancing or control device 11 which responds, its motor drive mechanism 11^b operating the speed changer Y to regulate the speed of rotation of pinch roller F until normal required temperature conditions of the metal strip are restored.

In the modification shown in Fig. 3, instead of passing the metal strip over a heating drum, I may pass it through an electric oven or other stationary heater which is illustrated diagrammatically at Z. The metal strip is drawn through the oven by the winding block I^x which may be driven by a suitable motor 38 whose speed may be controlled by the variable resistance or rheostat illustrated diagrammatically at 31. The rheostat arm 32 thereof is connected by the link 33 to the crank 25^x of the electric control unit 11^x.

and the said arm thereby responds to movement of the crank 25^x.

The radiation pyrometer P^x is arranged contiguous to the point of exit of the strip from the heater furnace Z and detects variation in temperature of the strip which it transmits to the electric control unit 11^x which, in turn, through the crank arm 25^x operates the rheostat 31 to regulate the speed of the motor 30 and consequently that of the winding block I^x and the strip as it passes through said furnace, whereby the temperature of said strip is maintained at the required point.

It is to be understood of course that the speed changing mechanisms in any of the modifications may be interchanged. Thus, for example, the drive and speed change mechanism controlled as in Fig. 1 may be substituted for the rheostat controlled motor drive of Fig. 3 to operate the winding roller I^x and vice versa the controlled motor drive 30 of Fig. 3 may be used to drive drum A of Fig. 1.

It is manifest, too, that the means of controlling the temperature of a moving substance to which heat is being applied is not applicable solely to the particular means of applying heat disclosed in my aforementioned patent or in the modifications above described. It is equally applicable even if the metal is heated for example by passing it between two electrical contacts, which cause it to be heated by a current of electricity passing through the metal from one contact to the other, whether the current be direct or alternating.

It is also apparent, moreover, that various means can be employed for heating the drum A interiorly or exteriorly; for example, an electrical heater could be employed, or one using oil as fuel.

Further, it is also apparent that other types of electric control devices besides the unit herein described could be employed as well as other types of speed changing means, those cited being by way of example only.

By my invention, it is possible to heat treat coils of large size in a very satisfactory manner. The degree of uniformity to which the strip is heated is much greater than that which can be obtained with the use of earlier heat treating apparatus or that of my aforementioned patent.

By my invention is is possible to obtain a very fine control of the crystal diameter of the metal strip, and it is also possible to secure uniform heating of all parts of a coil of strip metal. Furthermore, it is possible by the employment of relatively inexpensive apparatus to obtain uniform heating of all parts of large coils having many convolutions, and this is a result greatly desired by rolling mill operators at the present time.

By use of a heat responsive means as a radiation pyrometer directed against strip of metal as it leaves a heating member, in conjunction with an electric control device and in conjunction with a speed changing device, the latter may be operated to control the speed of the drum A, the pinch rolls F or the winding block I^x. By this means the speed of the metal is made responsive to any variation in the final temperature of the metal.

My new apparatus is not confined to the treat-

ment of strip metal and can be used for the treatment of wire and other materials.

Various changes may be made in the details of the apparatus, without departing from the scope of my invention as defined in the claims. 5

What I claim is:

1. In a device for heat treating strip metal wherein a rotatable hollow body with heating means for said body located within the same, an electric driving motor and pinch rolls adapted to be driven by said motor and engaging the strip to be heated whereby the latter is drawn over and in contact with said body are provided, a temperature responsive detecting device located adjacent the strip as it leaves the heating body and outside of the latter, an electric balancing motor drive operable through said temperature responsive detecting device and a variable speed device interposed between said first named electric motor and said pinch rolls, and operated by said electric balancing motor drive whereby the speed of said pinch rolls and consequently the speed of said feeding strip is responsive to the heat of the strip itself, said variable speed device including a grooved input disk and a grooved output disk, the first coupled to said electric motor and the second connected through intermediate means to one of said pinch rolls, tiltable rolling disks engaging both said input and output disks in the hollow portions thereof and means for connecting said rolling disks with said electric balancing motor drive to so tilt said rolling disks in said groove whereby the speed imparted to said output disk by said input disk may be varied. 35

2. In a device for heat treating strip metal wherein a rotatable hollow body with heating means for said body located within the same around which body the strip to be heated is drawn in intimate contact are provided, means for drawing said strip over said body, means for driving said drawing means, a variable speed device interposed between said driving means and said drawing means, a temperature responsive detecting device located adjacent the strip as it leaves the heating body and outside of the latter, an electric balancing motor drive controlled by said temperature responsive device and operating the variable speed device whereby the speed of said drawing means and consequently the feed of said strip is responsive to the heat of the strip itself. 45

3. In a device for heat treating strip metal wherein a rotatable hollow body with heating means for said body located within the same around which body the strip to be heated is drawn in intimate contact are provided, means for directing the strip in immediate conductive contact with the exterior of said body, gearing for rotating said hollow body, means for driving said gearing, a variable speed device interposed between said driving means and said gearing, a temperature responsive detecting device located adjacent the strip as it leaves the heating body and outside of the latter, an electric balancing motor drive controlled by said temperature responsive device and operating the variable speed device whereby the speed of said rotating body and consequently the feed of said strip is responsive to the heat of the strip itself. 55 60 65 70 75
